UNITED STATES PATENT OFFICE

2,692,620

METHOD AND APPARATUS FOR MAKING
DOUBLE CONICAL TORSION SPRINGS

Curt H. K. Sjoberhm, Worcester, Mass.

Application January 13, 1953, Serial No. 331,045

5 Claims. (Cl. 140—78)

1

This invention relates to a method and apparatus for making double conical torsion springs such as those which are used in spring doors. These springs have a reduced diameter portion in the center and increase in diameter outwardly toward each end. Because of this reduced diameter central portion, it is necessary to have two opposed arbors so that the formed spring can be removed therefrom. It is also necessary to keep the arbors in close contact throughout the forming of the spring. For that reason, the apparatus used prior to my invention required the use of a traveling or traversing wire feed and arbors which did not move axially during the formation of the spring. Such apparatus formed the springs at a relatively slow rate, required a complicated mechanism and did not form a spring of uniform pitch.

It is the object of my invention to provide apparatus for forming a double conical spring in which the wire is fed axially without traversing.

Another object is to provide such apparatus which will form springs of uniform pitch at a rapid rate.

Still another object is to provide a method of forming double conical springs at a rapid rate.

These and other objects will be more apparent after referring to the following specifications and attached drawings, in which:

Figure 1 is a top plan view of the spring making apparatus;

Figure 2 is a vertical view taken on the line II—II of Figure 1;

Figure 3 is a view taken on the line III—III of Figure 1, the upper portion of the coiling device being omitted except for the parts indicated by dotted lines;

Figure 4 is a view of the arbors showing a wire fed thereto ready to be coiled;

Figure 5 is a view, similar to Figure 4, showing the spring partially coiled;

Figure 6 is a view, similar to Figure 4, showing the completed spring;

Figure 7 is an enlarged view, partly in section, showing details of the arbor; and

Figure 8 is a view, similar to Figure 7, showing the arbors in engagement.

Referring more particularly to the drawing, the reference 2 indicates the winding arbor which can be rotated by mechanism 3 such as shown and described in the patents to Sleeper Nos. 1,045,900 and 1,368,297. A winding pin 4 is mounted on the bottom of a spindle 6 which also supports the arbor 2. The pin 4 is spaced a short distance from the arbor 2 for a reason which will appear later. The spindle 6 is reciprocated

2

in the usual manner by mechanism 7 such as shown and described in the above mentioned patents. Wire is fed in the usual manner through a wire cutter 8 by feeding mechanism 9 such as shown and described in the above mentioned patents. A cutter blade 10 (Figures 2 and 6) is mounted on a slide 12 which is reciprocated by means of a cam 14. A roller 16 mounted on the slide 12 contacts the cam 14 to move the slide 12 to cut the wire. A spring 17 retracts the slide 12. The cam 14 is mounted on a shaft 18 which is rotated in synchronism with the spindle feeding and rotating mechanism. A stop 20 is mounted for movement toward and away from the arbor 2 on a slide 22.

Mounted beneath arbor 2 in alignment therewith is an arbor 24. As shown in Figure 2 the arbor 24 is resiliently attached to the piston rod 26 of an air cylinder 28 in the following manner. The piston rod 26 has an axial opening 30 therein with a steel ball 32 mounted in the bottom thereof. A bushing 34 is mounted adjacent the ball 32. A collar 36 is provided on the arbor 24, the lower end of which is surrounded by a spring 38. The bottom end of the spring bears against the collar 36 and the top end against the bottom of a nut 40 which is screwed into the opening 30. The spring 38 cushions the shock of the contact between arbor 24 and the bushing 40 when the piston rod 26 reaches the bottom of its stroke. As shown in Figures 7 and 8 the top of the arbor 24 is provided with a spherical opening 42 for receiving a spherical portion 44 mounted on the bottom end of the arbor 2. Air is provided to the top of cylinder 28 through an air conduit 46 and to the bottom through a conduit 48. The end of conduit 46 is attached to a control valve 50 and the end of conduit 48 to a control valve 52. The control valves 50 and 52 are mounted adjacent the shaft 18 and are provided with levers 54 and 56, respectively, which extend downward and are actuated by means of cams 58 and 60 mounted on the shaft 18. Air is provided to the valves 50 and 52 through air reducing valves 62 and 64, respectively.

The operation of the device is as follows:

The arbor 2 is fed downwardly until it almost reaches its lowest position, at which time the cams 58 and 60 will actuate the valve 50 and 52 to introduce air through the conduit 48, thus snapping the arbor 24 up against the arbor 2 with the spherical portion 44 being received in the opening 42. The arbor 2 continues its downward movement pushing the arbor 24 ahead of it against the pressure of the air in the cylinder 28 until it reaches the position shown in Fig-

ures 2 and 4. In this position the arbor 2 is stationary and the winding pin 4 is so positioned that the wire W which is being fed will pass between the winding pin 4 and the arbor 2. Movement of the wire continues until it abuts against the stop 20 as shown in Figure 4. The arbor 2 is then rotated and raised in the usual manner so that the coils of the spring S are formed. The air in cylinder 28 holds the lower arbor 24 against the upper arbor 2 at all times during the winding of the spring. After the spring S has been completely wound, the cam 14 moves the cutter blade 10 over the wire cutter 8 to sever the wire W at the desired point as shown in Figure 6. As soon as the wire W is severed the cams 58 and 60 operate the valves 59 and 52 so that air is delivered through conduit 48 to the top of cylinder 28, thus rapidly retracting the lower arbor 24 from its highest position as shown in Figure 6. This permits the spring S to be discharged. The machine is then ready to fabricate another spring.

While one embodiment of my invention has been shown and described it will be apparent that other adaptations and modifications may be made without departing from the scope of the following claims.

I claim:

1. In apparatus for making a double conical spring from a length of wire, said apparatus having a rotatable reciprocating spindle, a conical arbor on the end of said spindle with its smallest diameter portion at the free end thereof, means for holding the end of said wire for rotary movement with said arbor, a second rotatable conical arbor in axial alignment with said first arbor, the smallest diameter portion of the second arbor facing the smallest diameter portion of the first arbor; the improvement comprising a stationary wire cutter adjacent said arbor through which wire is fed, a cylinder mounted in alignment with said arbors at the large diameter end of the second arbor, a piston in said cylinder, a piston rod connected to said piston, means connecting said second arbor to said piston rod, means for supplying a fluid to the outer end of said cylinder to hold said second arbor against said first arbor during formation of said spring, a cutting blade adapted to cooperate with said wire cutter to sever said wire when the spring is completed, and means for supplying a fluid to the inner end of said cylinder to retract said second arbor from said first arbor when the spring is completed and the wire cut.

2. In apparatus for making a double conical spring from a length of wire, said apparatus having a rotatable reciprocating spindle, a conical arbor on the end of said spindle with its smallest diameter portion at the free end thereof, a pin mounted on the end of said spindle adjacent said arbor, the distance between said pin and arbor being sufficient to receive said wire, a second rotatable conical arbor in axial alignment with said first arbor, the smallest diameter portion of the second arbor facing the smallest diameter portion of the first arbor; the improvement comprising a stationary wire cutter adjacent said arbor through which wire is fed, a stop in alignment with said wire cutter for stopping axial movement of wire fed through said wire cutter and between said pin and arbor, a male member on the small diameter end of one of said arbors, a female member on the small diameter end of the other of said arbors, a cylinder mounted below said bottom arbor in axial alignment therewith, a piston in said cylinder, a piston rod connected to said piston, means connecting said bottom arbor to said piston rod, means for supplying a fluid to the bottom of said cylinder to hold said bottom arbor against said top arbor during formation of said spring, a cutting blade adapted to cooperate with said wire cutter to sever said wire when the spring is completed, and means for supplying a fluid to the top of said cylinder to retract said bottom arbor from said top arbor when the spring is completed and the wire cut.

5 to said piston, means connecting said second arbor to said piston rod, means for supplying a fluid to the outer end of said cylinder to hold said second arbor against said first arbor during formation of said spring, a cutting blade adapted to cooperate with said wire cutter to sever said wire when the spring is completed, and means for supplying a fluid to the inner end of said cylinder to retract said second arbor from said first arbor when the spring is completed and the wire cut.

3. Apparatus for making a double conical spring from a length of wire, said apparatus comprising a rotatable reciprocating spindle arranged with its axis vertical, a top conical arbor mounted on the bottom of said spindle with its smallest diameter portion at the lower end thereof, a pin mounted on the bottom of said spindle, the distance between said pin and arbor being sufficient to receive said wire, a stationary wire cutter adjacent said arbor through which wire is fed, a bottom conical rotatable arbor in axial alignment with said top arbor, the smallest diameter portion thereof being at the top thereof, a cylinder mounted below said bottom arbor in axial alignment therewith, a piston in said cylinder, a piston rod connected to said piston, means connecting said bottom arbor to said piston rod, means for supplying a fluid to the bottom of said cylinder to hold said bottom arbor against said top arbor during formation of said spring, a cutting blade adapted to cooperate with said wire cutter to sever said wire when the spring is completed, and means for supplying a fluid to the top of said cylinder to retract said bottom arbor from said top arbor when the spring is completed and the wire cut.

40 4. Apparatus for making a double conical spring from a length of wire, said apparatus comprising a rotatable reciprocating spindle arranged with its axis vertical, a top conical arbor mounted on the bottom of said spindle with its smallest diameter portion at the lower end thereof, a pin mounted on the bottom of said spindle, the distance between said pin and arbor being sufficient to receive said wire, a stationary wire cutter adjacent said arbor through which wire is fed, a stop in alignment with said wire cutter for stopping axial movement of wire fed through said wire cutter and between said pin and arbor, a bottom conical rotatable arbor in axial alignment with said top arbor, the smallest diameter portion thereof being at the top thereof, a male member on the small diameter end of one of said arbors, a female member on the small diameter end of the other of said arbors, a cylinder mounted below said bottom arbor in axial alignment therewith, a piston in said cylinder, a piston rod connected to said piston, means connecting said bottom arbor to said piston rod, means for supplying a fluid to the bottom of said cylinder to hold said bottom arbor against said top arbor during formation of said spring, a cutting blade adapted to cooperate with said wire cutter to sever said wire when the spring is completed, and means for supplying a fluid to the top of said cylinder to retract said bottom arbor from said top arbor when the spring is completed and the wire cut.

45 5. The method of making a double conical spring on two opposed conical arbors having their small diameter ends facing each other which comprises feeding a wire axially past the large diameter end of the first of said arbors, gripping the fed wire to rotate with said first arbor, moving the second arbor against the first

arbor, rotating and retracting the first arbor in a direction away from the second arbor to coil the wire therearound, resiliently moving the second arbor to hold it against the first arbor as the first arbor rotates and retracts, continuing movement of both of said arbors with the arbors in engagement to coil the wire around both of said arbors, stopping rotation of said arbors, cutting the formed spring from said wire, and reTRACTING said second arbor from said first arbor to permit removal of said spring.
